UNITED STATES PATENT OFFICE.

REUBEN FRANCIS O'NEIL, OF OAKLAND, CALIFORNIA.

SAFETY COUNTER BILL FILE.

Application filed January 14, 1928. Serial No. 246,863.

This invention relates to improvements in bill files and particularly to files of that type which are used on the counters of grocery stores, restaurants, etc., for the purpose of receiving checks, tags, bills and other small papers.

The principal object of my invention is to provide a bill file having a spike for the impaling of the papers with a means for protecting the point of the spike in such a manner as to prevent any personal injury being done to any employee or any patron of the place of business in which the file is located, while at the same time allowing bills and the like to be applied in the usual way to the file by pressing said papers down upon the spike.

Essentially the protecting means comprises a guard normally disposed directly above and spaced a short distance from the point of the spike. A further object of my invention is to support this guard in such a manner that it may be shifted laterally clear of the spike so as to enable any number of bills on the file to be removed simultaneously if desired, or moved down to envelop the point of the spike.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a sectional elevation elevation of my improved bill file showing the parts in their normal positions.

Fig. 2 is a top plan view of the device.

Fig. 3 is a bottom plan view of the file showing the cover plate removed.

Fig. 4 is a fragmentary section showing the point protector or guard lowered over the plate.

Referring now more particularly to the characters of reference on the drawings, the support or base of the device is a circular member comprising a top plate 1 from which a side flange 2 depends all around the same to a certain depth so as to provide a chamber under the plate above the counter or table on which the flange rests.

A vertical rod 3 projects upwardly from the plate 1 adjacent one edge and at its lower end is fixed in a pedestal 4 turnably mounted in

the plate 1. At its upper end this rod is bent to extend substantially horizontal for a certain distance as shown at 5, this bent portion at its outer end terminating in a downwardly depending threaded stem 6. This stem is normally in vertical alinement with and spaced from a spike member 7 which at its lower end is secured in the plate 1 in diametrically opposed relation to the rod 3. Threaded on to the stem is a guard sleeve 8, whose vertical movement in either direction on the stem is limited by enlargements 9 on the opposite ends of the stem. These parts are so arranged that when the guard is at its upper limit of movement, the space between the bottom of the guard and the point of the spike is sufficient to permit of the impaling of bills, etc., on the spike as shown in Fig. 1 but is not sufficient to permit of a finger of the operator passing therebetween. When the guard is lowered to its limit of downward movement, it extends below and is disposed about the point of the spike somewhat as shown in Fig. 4.

It will therefore be seen that when the guard is in the first described position any papers may be readily placed on the spike while at the same time the point is covered from above so that there is no danger of its contacting with the hands, finger, or any other portion of the anatomy of any person accidentally coming against the file. When the guard is lowered the papers are positively prevented from being removed.

Secured to and projecting radially from the pedestal 4 under the plate is an arm 10 which extends towards the opposite edge of the plate. At the outer end of the arm an upstanding finger or thumb knob 11 is fixed, this knob projecting up through a slot 12 cut in the plate and curved concentric with the pedestal, said slot having an arcuate length of about 90°. A spiral spring 13 is disposed under the plate and is connected at one end to the arm and at the other end to the base 100 and acts to maintain the knob on the arm at one end of the slot, in which position the guard 8 is concentrically alined with the spike. It will therefore be seen that by moving the knob to the opposite end of the slot, 105 the rod 3 and the parts connected thereto will be turned through a 90° arc, so that the guard will then be moved clear of the spike and any or all of the bills impaled on the spike may be readily withdrawn as a unit from the spike. When the holding pressure on the knob is released the guard will automatically

move back to its point protecting position on account of the action of the spring 13.

To conceal and protect the parts under the base plate from damage or tampering, a cover 5 plate 14 is preferably secured to the flange of the base member under the arm and spring as shown in Fig. 1.

From the foregoing description it will be readily seen that I have produced such a device as substantially fulfills the objects of the 10 invention as set forth herein.

While this specification sets forth in detail the present and preferred construction of the device, still in practice such deviations from 15 such detail may be resorted to as do not form a departure from the spirit of the invention, as defined by the appended claims.

Having thus described my invention what I claim as new and useful and desire to secure 20 by Letters Patent is:

1. A bill file including a spike member on which to impale bills, a guard cap disposed in line with the spike, and a threaded stem on 25 which the cap is adjustably screwed; said stem being disposed in longitudinal alinement with the spike and spaced from the point thereof a predetermined distance.

2. A bill file including a spike member on which to impale bills, a guard normally in 30 line with the spike and beyond the point thereof, and movable means rigidly supporting the guard to enable the same to be moved laterally with regard to the spike.

3. A bill file including a spike member on 35 which to impale bills, a guard beyond and spaced from the point of the spike, a movable member supporting the guard and means applied to said member for normally maintaining the guard in longitudinal alinement with the spike while enabling said guard to be 40 moved laterally with respect to the spike.

4. A bill file including a spike member on which to impale bills, a guard beyond and spaced from the point of the spike, a movable member supporting the guard and including 45 a turnable element disposed parallel to the spike, means for turning said element, and means applied to the turning means for normally maintaining the guard in longitudinal alinement with the spike. 50

5. A bill file including a spike member on which to impale the bills a guard beyond and spaced from the point of the spike, a movable member supporting the guard and including a turnable element disposed parallel to the 55 spike, a common base member in which the spike and element are mounted, an operating arm applied to said element, means between the arm and base for limiting the arc of turning movement of said element, and spring 60 means for holding said element at one end of such arc, the guard being then longitudinally alined with the spike.

6. A bill file including a spike member on which to impale the bills, a guard beyond and 65 spaced from the point of the spike, a movable member supporting the guard and including a turnable element disposed parallel to the spike, a common base member in which the spike and element are mounted in spaced relation to each other; said base having a top 70 plate with a chamber thereunder, an operating arm connected to and extending radially from said element under the plate, a knob projecting from the outer end of the arm 75 through a slot in the plate curved concentric with said element, and a spring acting to yieldably hold the knob at one end of the slot; the guard being then in longitudinal alinement with the spike. 80

In testimony whereof I affix my signature.
REUBEN FRANCIS O'NEIL.
